DYEING MACHINE

Frederick Carter and Donald C. Taylor,
Westhill, Ontario, Canada

Application October 21, 1944, Serial No. 559,825

1 Claim. (Cl. 68—175)

1

The invention relates to improvements in a dyeing machine of the class in which a material to be dyed is guided through a vat or tank in a continuous manner and which is adapted for use in connection with a sewing machine so that a thread may be dyed in different colors as required without having to change from one spool to another.

More particularly the invention concerns a dyeing machine comprising a case of box-like formation in which a series of dyeing vats are contained for holding dyes of different colors. The case has a hinged lid which carries a slide shiftable over the vats by means of an elongated slot. The slide has guides for a thread unwound from a spool by the operation of a sewing machine. The guides include a depending standard for extending into a vat and a cross arm for guiding the thread downwardly to the bottom of the standard and then upwardly therefrom for travel to the head of the sewing machine. By this arrangement the slide may be slid along the lid to bring the guides into proper position over a vat for dyeing the thread a desired color. The reaches of the thread between the standard and the cross arm have wiping contact with the vat for removal of excess dye and to ensure of uniform dyeing operation.

By virtue of this machine the color of the thread can be quickly and readily changed by raising the cover of the case to remove the thread from one vat and shifting the slide along to another vat and lowering the lid to enable the thread to travel through such other vat in the running of the sewing machine. The changing of the color is an exceedingly simple operation that can be performed expeditiously by the operator. The machine obviates the necessity of using a multiplicity of spools of differently colored thread particularly where sewing operations require change of color of the thread for a short interval.

In such a dyeing machine it is highly desirable that the slide be constructed so as to be freely movable from one position to another without any tendency to bind or stick. Hence it is a major object of the invention to provide a slide mechanism of improved construction having salient features of advantage.

Another object of the present invention is to supply a slide with a simple and efficient indexing device.

A still further object is to furnish a more serviceable dyeing machine which can be manufactured at low cost.

2

The objects are obtained by the selected embodiment of the invention illustrated in the accompanying drawing in which:

Fig. 1 is a perspective view of a dyeing machine embodying the present invention.

Fig. 2 is a cross-sectional view thereof taken on line 2—2 of Figure 1.

Fig. 3 is a vertical section of Fig. 2 on line 3—3 thereof.

Fig. 4 is a perspective fragmentary detail illustrating the slide mechanism.

Fig. 5 is a side view of the slide.

Like numerals of reference indicate corresponding parts in each of the figures throughout the drawing of the invention.

The dyeing machine to which my invention relates comprises a case 10 of box-like formation adapted to contain one or more rows of dye vats or tanks 11 for the different colors which may be required. The vats are suitable receptacles arranged in fixed positions by suitable means and the case is an elongated member of a capacity to contain the desired number of vats.

The lid 12 of the case is hinged at 13 to swing upwardly toward one side for rendering the interior accessible and is provided with a longitudinal slot 14 forming a guideway over the vats for the slide 15. The standard is denoted at 16 and the lower end thereof has an eye 17. The upper end carries the cross arm 18 which is secured medially of its length thereto and is provided with an eye 19 at each end. The eyes 17 and 19 guide the thread 20 as it is unwound from a spool 21 carried by a holder 22 at an end of the case. The opposite end of the case has a guide member 23 through which the thread is passed for subsequent threading through the sewing machine.

Having recounted the dyeing machine to which my invention relates the invention itself will be described in detail. The improved structure of the slide mechanism comprises forming the slide 15 of a flat strip of metal bent into a substantially U-shaped configuration having a

bight 24 to which the standard 16 is secured and having converging legs 25 extending downwardly with their lower ends engaged with the respective edges 26 of the slot 14 under light tension. The extremities of the said lower ends are bent outwardly, as at 27, to fit under the lid 12. The bent extremities 27 are in the nature of flanges bearing against the bottom face of the lid and serving to retain the slide 15 in proper position over a vat with the standard 16 depending therein and the reaches of the thread con-

tacting the mouth of the vat so as to wipe off excess dye.

The slide is made of a material of a resilient nature and the legs 25 frictionally engage the edges of the slot 14 with sufficient firmness to assure of its being retained in any position in which it may be set. The material of the lid at the edges of the slot is desirably upturned to form narrow flanges as at 28 which present a smooth slide surface for contact with the lower ends of the legs 25. Due to the convergency of the legs the flanges thereof form guide grooves for the slide.

To shift the slide along the slot in changing from one color to another it is merely necessary to grasp it by hand and squeeze the legs so that it may move freely to a new position, it being understood that the lid is first swung upwardly so that the vats will not interfere with the travel of the standard 16.

It is most important that the standard be positioned exactly at the centre of a vat in order that the thread may have proper wiping contact with the top edge portion thereof. For this purpose an indexing device may be employed. Such an indexing device may comprise the provision of an aperture 29 in one of the legs 25 of the slide and rounded nodules 30 formed on the corresponding edge of the slot 14. The nodules are located at intervals alongside the slot according to the spacing of the vats and may be formed by struck up parts of the lid material. By this arrangement the aperture 29 will engage a nod-

ule over a vat as the slide is moved along the slot and this will properly index the slide.

The advantages and utility of the invention will be manifest from the preceding description and it will be evident any number of vats may be used either in one or more rows.

What we claim is:

In a dyeing machine of the class described, comprising a case for containing a row of vats and having a hinged cover including material guide means projecting through an elongated slot in said cover for movement from one to another of said vats, the improvement including slide means for supporting said material guide means, said slide means including a substantially U-shaped member of springy material having converging legs flanged at their distal ends for interfitting engagement with side edges of said slot under outward tension, said material guide means being attached to the bight portion of said U-shaped member and having a material guiding element extending between said legs and protruding therefrom for projecting into one or another of said vats according to the position of the slide means, and an indexing device for said slide means comprising nodules on said cover of the case spaced at intervals along one edge of the slot therein for engaging in a locating aperture provided in the adjacent leg of said U-shaped member.
